DESIGN FOR A CYCLE SADDLE SEAT

Harold L. Van Doren, Toledo, and John G. Rideout, Perrysburg, Ohio, assignors to The American-National Company, Toledo, Ohio, a corporation of Ohio

Application September 16, 1935, Serial No. 58,579

Term of patent 7 years

To all whom it may concern:

Be it known that we, Harold L. Van Doren and John G. Rideout, both citizens of the United States of America, residing at Toledo and Perrysburg, respectively, in the counties of Lucas and Wood, respectively, in the State of Ohio, have invented a certain new, original, and ornamental Design for a Cycle Saddle Seat, of which the following is a specification, reference being had therein to the accompanying drawing, forming a part thereof, wherein:

Figure 1 is a top plan view of a saddle seat showing our new design;

Figure 2 is a side view thereof;

Figure 3 is a rear view thereof.

We claim:

The ornamental design for a cycle saddle seat substantially, as shown.

HAROLD L. VAN DOREN.
JOHN G. RIDEOUT.
